UNITED STATES PATENT OFFICE

ALFRED E. GARDNER, OF ASHLAND, NEW JERSEY

DESIGN FOR AN EMBLEM OR SIMILAR ARTICLE

Application filed October 18, 1930. Serial No. 37,803. Term of patent 3½ years.

To all whom it may concern:

Be it known that I, ALFRED E. GARDNER, a citizen of the United States, residing at Ashland, in the county of Camden and State of New Jersey, have invented a new, original, and ornamental Design for Emblem or Similar Article, of which the following is a specification, reference being had to the accompanying drawing, forming part thereof.

Fig. 2 is an edge view of the same.

I claim:

The ornamental design for an emblem or similar article as shown.

ALFRED E. GARDNER.
